(57) **CLAIM**

The ornamental design for a motorcycle saddlebag side trim, as shown and described.

DESCRIPTION

FIG. 1 is a top perspective view of the motorcycle saddlebag side trim of the present invention.

FIG. 2 is a side perspective view of the motorcycle saddlebag side trim of FIG. 1.

FIG. 3 is a rear perspective view of the motorcycle saddlebag side trim of FIG. 2.

FIG. 4 is a rear perspective view of the motorcycle saddlebag side trim of FIG. 1 as viewed from the left end of FIG. 1.

FIG. 5 is a front perspective view of the motorcycle saddlebag side trim of FIG. 1 as viewed from the right end of FIG. 1.

FIG. 6 is a top perspective view of the motorcycle saddlebag side trim of FIG. 1; and,

FIG. 7 is a bottom perspective view of the motorcycle saddlebag side trim of FIG. 1.

The broken lines indicate that the rear surface and mounting elements on the rear surface form no part of the claimed design.
